RECORD CHANGING MECHANISM FOR
PHONOGRAHS

Thomas W. Small, Fort Wayne, Ind.; Anna M. Small, executrix of said Thomas W. Small, deceased, assignor, by means assignments, to Farnsworth Television & Radio Corporation, Fort Wayne, Ind., a corporation of Delaware

Application October 5, 1939, Serial No. 298,092

17 Claims. (Cl. 274—10)

This invention relates to an automatic record changer for disk record phonographs wherein the stack of records is supported above the turntable, the lowermost record of the stack being released to drop by gravity upon the turntable for reproduction.

The principal object of the invention is to enable a selective record changing mechanism to be produced with a minimum of working parts so as to be capable of economical production and take up little space in the phonograph. Thus, the invention is primarily directed toward improving upon record changers of this type in the direction of simplified mechanism.

One feature of the invention resides in the simplified adjustable record support for groups of either ten or twelve inch records, whereby a simple pivotal movement will alter the support for accommodating either size of record.

Another feature of the invention resides in the mechanism for releasing the lowermost record while supporting the superimposed records. This is accomplished by an extension of the centering pin so as to provide an eccentric portion, coupled with means for lowering one of the supports to permit the center hole of the lowermost record to be engaged by the eccentric portion, which, in its rotary movement, will slide the record first in one direction and then the other to release its opposite supported sides alternately.

Another feature of the invention resides in the curved formation of the center pin extension which imparts frictional resistance to the dropping of the record thereover, as well as imparts an eccentric movement thereto so that it will fall easily upon the turntable or preceding records.

A further and important feature of the invention resides in a new and novel trip mechanism for initiating the record changing cycle upon the reproducer moving inward with a spiral groove or oscillating by engagement with an eccentric groove. This is accomplished by a pair of interacting contacts for closing a circuit through a tripping solenoid, one of said contacts being mounted on the end of a hook movable with the tone arm while the other contact is on a freely moving pivoted arm carried within the hook. Thus, when the tone arm is moved inwardly by a spiral groove, it engages the arm and moves it into contact with the end of the hook. When the tone arm is given a reverse movement by an eccentric groove, it moves the hooked end thereof backwards to engage the contact on the arm.

The full nature of the invention will be under-

stood from the accompanying drawings and the following description and claims:

Fig. 1 is a plan view of the record changer with the unplayed records removed. Fig. 2 is a side elevation thereof showing a group of records supported over the turntable, and on the turntable in playing position. Fig. 3 is a rear elevation of the record changer. Fig. 4 is a bottom plan view showing the underside thereof. Fig. 5 is a partial view showing a side elevation of the record supports for twelve inch records. Figs. 6 and 7 are illustrative figures showing the various positions of the record when released. Fig. 8 is a top plan view of portions of the actuating mechanism showing them in position during the playing of a record. Fig. 9 is a side elevation of portions of the actuating mechanism during the playing of a record. Fig. 10 is a view of the record trip arms when in record changing position. Fig. 11 is the same as Fig. 10 in record playing position. Fig. 12 is the same as Fig. 11 upon reverse movement of the tone arm by an eccentric record groove. Fig. 13 shows the position of the arms when actuated by a spiral lead-in groove in the record. Fig. 14 is a wiring diagram showing the circuits and switches.

In the drawings there is shown a record changing and reproducing mechanism including a base plate 10 supporting a horizontally rotatable turntable 11 carrying one or more records 12 thereon, the uppermost record of the group carried by the turntable being positioned for reproduction. The unplayed records 12 are supported in a stack or group immediately above the turntable and spaced therefrom in position for release of the lowermost record for permitting it to drop by gravity into playing position on the turntable. Associated with the turntable there is the usual reproducer 13 mounted on the end of the tone arm 14.

The unplayed records 12 are centered in stacked formation above the turntable by an overhead centering pin 15 carried by a swinging arm 16 pivoted at its supported end upon an upright standard 17 extending upwardly from the base plate 10.

With the unplayed group of records 12 positioned by the pin 15, their opposed peripheral edges are supported by the plates 18a and 18a, provided said records are of the ten inch size. If said records are of the twelve inch size, they are supported by the plates 18b and 19b, as illustrated in Fig. 5.

The plates 18a and 18b are integral, being rotatably supported at the proper height upon a

post 20 slidable and rotatable within a tubular standard 21, said standard being supported upon the base plate 10. The post 20, being both slidably and rotatably mounted in the standard, is held in its lower position by a spring 22 and is provided with oppositely-extending lugs 23 at its upper end which are seatable in the notches 24 of the standard. Thus, said supporting plates may be turned to any desired 90 degree angle and locked in position. When positioned to support ten inch records, said plates are rotated and locked in the position shown in Figs. 1 and 2. When supporting twelve inch records, said plates are rotated 90 degrees and locked in the opposite position, as shown in Fig. 5.

The plates 19a and 19b are correspondingly adjustable for accommodating either size of records. For this purpose the plate 19a is horizontally pivoted between the uprights of standard 17 upon a horizontally extending rod 25 supported by the brackets 26 carried by the shafts 27. Thus, supporting plate 19a may be swung to a lower position for supporting ten inch records, as in Figs. 1 and 2, or swung upwardly to a vertical position out of the way, so as to expose the plate 19b which is positioned for supporting twelve inch records, as shown in Fig. 5. Plate 19b is supported directly upon the shafts 27 which are slidable with and guided by a cross head 28 within the standard 17. Said shafts with the supporting plates carried thereby are normally maintained in uppermost position under tension of the springs 29, in which position they support the unplayed records free of the record releasing member, as hereinafter described.

The lower ends of said shafts 27 slidably extend through the base plate 10 and have their lower ends connected below said plate to a cross bar 30 which has its upper surface engaged by one end of a pivoted lever 31 (Figs. 3 and 4). Said lever is pivotally supported by a suitable bracket 32 depending from the underside of the base plate 10. The opposite end of said lever is positioned to be engaged and actuated by the master cam, as hereinafter described, for pressing the bar 30 downwardly against the tension of springs 29 to lower the supporting plates 19a and 19b when the bottom record is to be released.

The centering pin portion 33 of the turntable is horizontally displaced (Fig. 2) to the left of pin 15 and extends upwardly in the usual cylindrical form to the height at which the played records may accumulate upon the turntable. However, said pin is prolonged in curved formation to provide a hook-like camming portion 34 terminating in a head 35 the vertical axis of which is horizontally displaced with respect to that of portion 33. As illustrated in Fig. 2, head 35 lies to one side of and immediately below the periphery of the overhead centering pin 15. Thus, the head 35 rotates with the turntable through a circular path transverse of the center hole of the lowermost unplayed record and eccentrically of the axial center of pin 15.

The unplayed records 12 are normally carried by their supporting plates in a plane above the head 35 so as not to be engaged thereby. But when the plates 19a, 19b are lowered by the action of the lever 31, the lowermost record of the group drops to a position where its center hole is engaged by the head 35. The eccentric movement of said head engaging with the record will slide it first to the left (Fig. 2), so that its right-hand edge will disengage the supporting plates 19a or 19b. Its left-hand edge will still be supported by

the plates 18a or 18b until the right-hand side drops down on the more extensively curved camming portion 34 which will act to throw the record to the right for disengaging its left-hand edge from said last-mentioned plates. The record then continues to oscillate by its engagement with the curved portion 34 and to move downwardly, but restrained by the friction resulting from the said curved portion, until it reaches the centering pin portion 33, whereupon said record will be properly centered in playing position. This movement is diagrammatically illustrated in Figs. 6 and 7.

For driving the record changing mechanism, 15 there is provided the usual electric motor 36 having a drive shaft 37 carrying a spur gear 38 adapted to mesh with a cam driving gear 39. Shaft 37 has a direct drive connection with the turntable and centering pin 33. At one point in the 20 periphery of the cam gear 39 the teeth are removed, as shown in Fig. 8. Said cam gear 39 is formed about the periphery of the cam member 40 suspended upon a shaft 41 extending downwardly from the underside of the base plate 10. 25 The motor 36 is similarly supported from the underside of the base plate 10 by the hangers 42.

The motor shaft 37 immediately above the gear 38 is provided with a radially-extending pin 43 adapted to engage a finger 44 pivotally mounted 30 on the hub portion of the gear 39, so that when in one position it will be engaged by pin 43 and when in another position it will be raised above said pin so as to be cleared. Said finger extends into position to be engaged by said pin adjacent that 35 portion of the gear 39 indicated at 45 which is mutilated so as to have no interengagement with the gear 38. By means of this arrangement, and wherein the shaft 37 and pin 43 are continuously 40 rotating with the gear 38, when the finger 44 is elevated about its pivotal mounting out of the path of the rotating pin 43, there will be no driving engagement between the spur gear and the cam gear. In this position the cam gear remains 45 at rest so that the record changing mechanism will not be operated while a record is being reproduced through the rotation of the turntable driven by shaft 37.

Said finger 44 has its opposite end engaged by 50 a bell crank lever 46 pivoted to the underside of the plate 10 at 47, which lever is actuated by a solenoid 48. With said bell crank lever 46 in normal position, the adjacent end of finger 44 is engaged thereunder so that the other end is held above the path of the pin 43, as illustrated 55 in Figs. 8 and 9. Upon actuation of said solenoid by the trip mechanism, the bell crank 46 will be withdrawn from finger 44, whereupon it will drop into position to be struck by the pin 43. When pin 43 strikes said finger, it partially rotates the 60 cam gear 39 sufficient to cause its teeth to mesh with those of the gear 38. Thereupon the gear 39 and cam 40 will be rotated one revolution, during which rotation the finger 44 engages with a 65 pending cam track 49 fixed to the underside of the base plate 10, as shown in Fig. 9. As it passes under said cam track 49, its opposite end is raised and in that position it leaves cam track 49, but is simultaneously engaged under bell crank lever 46 which continues to hold its raised 70 end out of the path of pin 43 until the solenoid 48 again retracts the bell crank lever 46. With said finger 44 thus held out of the path of pin 43, and at that point the cam gear 39 being mutilated, it will come to rest during the next 75 record playing operation.

By means of the above arrangement a simple mechanism is utilized for driving the cam 40 a single revolution upon energizing the solenoid 48 for actuating the record changing mechanism, said cam and mechanism automatically coming to rest upon the completion of the cycle for permitting free rotation of the turntable and reproduction of the record until the solenoid is again energized upon the record being completed.

From the above it will be noted that the cam 40 will be driven one revolution upon actuation of the solenoid 48 and upon completion of the single revolution will come to rest. The cam 40 acts to first elevate the tone arm 14 to lift the reproducer 13 from the record, swing the tone arm clear of the record, and then lower the record supporting plates 19a, 19b to cause the lowermost record to become engaged by the head 35 for releasing it to drop into playing position. Thereupon the reproducer is returned to overlie the start of the record and is lowered thereon. The cam then comes to rest to permit reproduction of the record in the usual way until the reproducer reaches the end of the record where it will cause the solenoid 48 to be energized for again initiating the cycle of movement of said cam.

The first action caused by the cam when it starts to revolve is effected by the cam surface 50 extending downwardly with which a roller 51 engages and over which it rides during the rotation thereof. The roller 51 is mounted on a lever 52 pivotally supported intermediate its ends at 53 by a depending ear extending downwardly from the base plate 10. The opposite end of the lever from the roller supports a tone arm raising pin 54 vertically slidable in a suitable guide on the base plate so that when elevated by the lever, it engages the underside of the tone arm 14 and raises it free of the record being reproduced. The tone arm is pivotally mounted for such movement at 55 on a standard 56 supported from the top of the base plate 10. The weight of the tone arm maintains the roller 51 in contact with the cam surface 50 and permits lowering of the reproducer into playing position when the cam allows the roller 51 to be raised under the tone arm weight.

The next movement is to swing the tone arm free of the record. For this purpose there is provided a bell crank lever 57 fulcrumed upon a stud 58 depending from the base plate 10. The free end of the lever engages an ear 59 secured to a shaft 60 extending vertically upwardly and rotatably supported within the standard 56, said shaft being secured at its upper end to the tone arm. The actuated end of the lever 57 is engaged by a cam surface 61 during rotation of the cam 40, forcing the engaged end of the lever outwardly and the engaging end of the lever inwardly against the ear 59 for rotating the shaft 60 to swing the reproducer away from the record. This movement swings the opposite end of the ear 59 against the free end of a pivoted arm 62 pivoted at 63 to the underside of the plate 10. Said arm is thereby moved against the tension of a spring 64 having one end connected to the arm and the other end anchored to a plate 65. Thus, the tone arm is swung outwardly by the action of the cam 61 and is swung inwardly by the spring 64 as the cam permits.

The tone arm may be adjusted to operate on either ten or twelve inch records by the manually operated knob 66 which may be turned within a bearing sleeve 67 and carries a shaft 68 at its lower end which is oblong in cross section. The

arm 62 bears against shaft 68 so that it is positioned thereby to limit the inward swinging movement of the tone arm. Shaft 68 is so formed and positioned that when it is turned so that its narrow edge is engaged by arm 62, the tone arm of the reproducer will be swung back to position it for a twelve inch record. When the knob 66 is turned so as to present the broad side of said shaft 68 to the arm 62, the spring 64 will move said arm inwardly a slightly greater distance, which in turn will swing the reproducer inwardly to set it for a ten inch record.

After the tone arm has been thus swung clear of the record, a new record is released to drop into playing position on top of the turntable or reproduced record. As above described, the bottom record is released by lowering the plates 19a, 19b until the lower record is engaged by the head 35. This lowering movement is effected by the lever 31 engaging the cross bar 30 and forcing it downwardly. To do this, the opposite end of lever 31 is engaged and elevated by an upwardly-extending cam surface 69. Thus, after the cam member 40 is rotated sufficiently to cause the tone arm to be swung out of position, the cam surface 69 passes under the end of lever 31 to raise it and force the cross bar 30 downwardly to lower the records 12 and permit the lowermost record to be engaged by the head 35. Immediately upon such engagement, said lever is released so that the springs 29 return the supporting plates to normal position so that the remaining records will be supported free of the head 35.

For tripping the mechanism at the end of the record by energizing solenoid 48, there is provided a pair of contact members 70 and 71. When said members move into electric contact, they close the circuit through the solenoid 48. Member 70 is supported by an arm 72 secured to shaft 60 of the tone arm so as to swing therewith. The member 71 is mounted upon an arm 73 freely pivoted to swing in the same plane as arm 72. Arm 72 carries an adjustable plate 74 in position to engage arm 73. Said arm 73 normally extends between the plate 74 and the contact 70 of the arm 72 so as to be embraced therebetween, as well as normally spaced therefrom. The radial length of arm 73 with respect to its pivotal mounting is substantially less than that of arm 72, whereby the contact 71 will travel through an arc of less radius than contact 70. This arrangement causes them to move toward and away from each other in a substantially radial direction during the course of their swinging movement.

In Figs. 10 to 13, inclusive, the different positions of the contacts are illustrated. Looking upwardly from the underside, in Fig. 10, the arm 72 is shown swung away from the center of the turntable by the tone arm to its maximum outward position. The contact 70 is in engagement with the end of the insulated arm 73 and out of contact with contact 71. As the arm is moved inwardly during the playing of the record, as shown in Fig. 11, arm 73 is disengaged by contact 70, but is pushed by plate 74. As their relative swinging movement continues, contact 71 moves toward alignment with contact 70. Toward the end of the record, as shown in Fig. 12, the contacts are in alignment, but are still out of contact. However, if the needle runs into an eccentric groove, the swinging movement of arm 72 will be reversed so that contact 70 will be moved into engagement with contact 71 to energize the solenoid.

If the needle is operating in a spiral groove record, the arms move to the position illustrated in Fig. 13, where the plate 74 finally pushes contact 71 into engagement with contact 70, due to the extreme inward swinging of the tone arm by the spiral lead-in grooves. Thus, solenoid 48 will be energized through the reverse movement of the tone arm by an eccentric groove (Fig. 12), or by the extreme inward movement of the tone arm by a spiral groove (Fig. 13).

As shown in Fig. 14 an anti-chatter switch 75 is in series with contacts 70, 71. Said switch 75 is actuated by the short arm of bell crank lever 46 so that when said lever is in normal position for retaining the finger 44 out of the path of pin 43, said switch is closed so as to complete the circuit through the solenoid upon contact of the trip 10, 71. But immediately upon the solenoid being energized by the trip, switch 75 is opened by said bell crank lever so that the circuit will be broken and thereby prevent chattering of the solenoid while the tone arm is being swung outwardly. For this purpose the released end of finger 44 engages the inner curved edge of lever 46 to hold it against the tension of spring 76 and thereby hold switch 75 open until the lever is disengaged by the continued movement of the finger. Thereafter spring 76 returns the bell crank lever to normal position to again engage finger 44 when it rides under cam 49, as well as permit switch 75 to close so that the trip switch may again complete the circuit.

In parallel with the trip switch and anti-chatter switch there is a reject switch 77 in the form of a button, shown in Fig. 1. By closing switch 77 the solenoid will be actuated in the same manner as by the trip switch so as to initiate the record changing mechanism.

The motor 36 is in circuit with a hand-controlled snap switch 78 and also a hold-in switch 79 in parallel therewith. The hold-in switch is normally closed but is opened by the cam surface 80 when the cam member 40 reaches the position wherein the tone arm is swung to its outermost position. Thus, when it is desired to stop the machine and discontinue its operation, the switch 78 may be moved to off position so as to break the circuit therethrough. However, the circuit through the motor will continue to be closed by the normally closed hold-in switch 79 until the tone arm is swung to its outer position, whereupon cam 80 will open said switch and break the circuit to motor 36 until the motor switch 78 is again moved to "on" position.

The invention claimed is:

1. An automatic record changer for a phonograph having a turntable, a pair of spaced supports for supporting a group of records at their opposite peripheries above said turntable, means for rotating the turntable, means rotatable with the turntable in eccentric relation to the central opening of the lowermost supported record and engageable with the wall of the central opening in the lowermost record adapted to slide it laterally first in one direction to free it from one of said supports and then the other to free it from the other of said supports, and means driven by said turntable rotating means operable to lower one of said supports to bring the said lowermost record into position to be engaged by 70 said rotatable means.

2. An automatic record changer for a phonograph including a turntable, an overhead support comprising a pair of spaced members upon which a group of records are supported at their oppo-

site peripheries above said turntable, a member eccentrically positioned with respect to the axis of said group of records and extending upwardly from the turntable in position to be engaged by 5 the wall of the central opening in the lowermost record, means for rotating said turntable and member, and means actuated by said turntable driving means and associated with said support operable to move said lowermost record of the 10 group into position to cause the wall of the central opening therein to be engaged by said member, whereby said rotating member will act to shift said engaged record laterally to free it from said support.

3. An automatic record changer for a phonograph including a turntable, a support comprising a pair of spaced members upon which a group of records are supported at their opposite peripheries above said turntable, a centering pin for said records extending upwardly from and rotatable with said turntable, means for rotating said turntable and pin, an extension on said centering pin having a portion eccentrically positioned with respect to the axis of the central opening of the lowermost record, said portion rotating with the turntable immediately below the lowermost record, and means actuated by said turntable rotating means and associated with one of said members operable to move said lowermost record into position to bring the wall of the central opening thereof into engagement with said eccentric portion, whereby said record will be engaged and shifted laterally thereby to free it from said support.

35 4. An automatic record changer for a phonograph including a turntable, a support comprising a pair of spaced members upon which a group of records are supported at their opposite peripheries above said turntable, a centering pin extending upwardly from and rotatable with said turntable, means for rotating said turntable and pin, an angular extension on said centering pin terminating in a head immediately below the central opening of the lowermost record, said head being carried by said extension eccentric of the axis of the central opening of the lowermost record, and means actuated by said turntable driving means and associated with one of said members operable to lower the lowermost record to permit the wall of its central opening to be engaged by said head and moved laterally thereby out of supporting engagement with one of said members and permit it to drop onto the angular portion of said extension, said extension being so formed as to move it laterally by its 50 rotary movement in the opposite direction to free it from the other supporting member.

5. An automatic record changer for a phonograph including a turntable, means adapted to support a group of records above said turntable, record shifting means for rotating said turntable, means rotatable with the turntable extending in alignment and engageable with the wall of the central opening in the lowermost record, and means associated with said supporting means actuated by said turntable rotating means operable to lower said record to permit the wall of its central opening to be engaged by said shifting means, said shifting means comprising a portion disposed eccentrically of the central opening of said lowermost record and operable to shift said record laterally free of said support.

6. An automatic record changer for a phonograph including a turntable, means for support-

ing a group of records above said turntable, means for rotating said turntable, a centering pin rotatable with said turntable, an extension on said pin terminating in a head positioned eccentrically of the centering aperture of the lowermost record and to register with the centering aperture in the lowermost record, said extension being angled away from the axis of rotation intermediate the centering pin and head, and mechanism actuated by said turntable rotating means and associated with said supporting means operable to lower the lowermost record to permit it to be engaged by said head, whereby said record will be shifted laterally by said head free of said supporting means.

7. An automatic record changer for a phonograph comprising a turntable, a pair of spaced supports upon which a group of records are supported at their opposite peripheries above said turntable, means for rotating the turntable, means associated with said supports for centering said records in supported position thereon, an upstanding spindle rotatable with the turntable and displaced with respect to said centering means, said spindle having its upper end terminating eccentrically of said centering means, and mechanism actuated by said turntable rotating means and associated with one of said supports operable to lower the lowermost record to permit the wall of its central opening to engage the eccentric upper end of said spindle, whereby said record will be shifted thereby to free it from said supports.

8. An automatic record changer for a phonograph comprising a turntable, a pair of spaced supports upon which a group of records are supported at their opposite peripheries above said turntable, means for rotating the turntable, means associated with said supports adapted to center said records through their center hole, an upstanding spindle rotatable with the turntable and displaced with respect to said centering means, said spindle having an intermediate portion curved out of alignment and its upper end eccentrically positioned relative to said centering means, and mechanism actuated by said turntable operating means operably connected to one of said supports for lowering it to present the wall of the central opening in the lowermost record to the upper end of said spindle, whereby said record will be reciprocated thereby to free it from said supports.

9. An automatic record changer for a phonograph including a turntable, an overhead support comprising a pair of spaced members upon which a group of records is supported at the opposite sides of its periphery above and in spaced relation to said turntable, means for rotating said turntable, a centering pin on said turntable extending upwardly therefrom and displaced with respect to the axis of the central opening in the lowermost record, said centering pin having an eccentric extension thereon positioned to be engaged by the wall of the central opening in the lowermost record of the group, and means actuated by said turntable rotating means and associated with one of said members operable to drop the lowermost record into engagement with said eccentric portion, whereby the rotation thereof with the turntable will shift said record laterally to free it from said support.

10. An automatic record changer for a phonograph including a turntable, an overhead support comprising a pair of spaced members upon which a group of records is supported at the op-

posite sides of its periphery above and in spaced relation to said turntable, means for rotating said turntable, a centering pin on said turntable extending upwardly therefrom toward the central portion of said group of records, said centering pin having an angular extension thereon positioned to be engaged by the wall of the central opening in the lowermost record of the group, and means actuated by said turntable rotating means and associated with one of said members operable to drop the lowermost record into position for engagement with said angular portion, whereby the rotation thereof with the turntable will oscillate said record to free it from said support.

15. 11. An automatic record changer for a phonograph including a turntable, an overhead support comprising a pair of spaced members upon which a group of records is supported at the opposite sides of its periphery above and in spaced relation to said turntable, means for rotating said turntable, a centering pin on said turntable extending upwardly therefrom and displaced with respect to the central opening in the lowermost record, said centering pin having an extension thereon positioned to register with the wall of the central opening in the lowermost record of the group, a reproducer for reproducing a record on the turntable, a trip mechanism actuated by the reproducer upon completing said reproduction, and means actuated by said trip mechanism and associated with one of said members operable to drop the lowermost record of the group into position for engagement by said eccentric portion, whereby the rotation thereof with the turntable will shift said record laterally to free it from said support.

20. 12. An automatic record changer having a turntable, a support positioned relative to said turntable for supporting a group of records in spaced axial alignment thereabove, a centering pin fixed to said turntable to extend upwardly therefrom centrally of said records, said centering pin being provided with a portion eccentrically disposed with respect to the central opening of the lowermost record, means for rotating said turntable, and means actuated by said turntable rotating means and associated with said support operable to drop the lowermost record of the group to a position for effecting engagement between the wall of its central opening and said eccentrically disposed portion, whereby said record will be shifted laterally thereby to release it from said support.

25. 13. A record changing apparatus comprising a rotatable turntable for receiving a record to be played; two diametrically opposite supports with respect to said turntable for supporting a stack of records over said turntable by engaging portions of the peripheral edge of the lowermost supported record, one of said supports being adapted to be moved; a member extending upwardly from and being rotatable with said turntable in eccentric relation to the centering aperture of the lowermost supported record; and means operatively connected to said movable support for moving the wall of the centering aperture of said lowermost supported record into the path of said member whereby the rotation of said member disengages successively the peripheral edges of said lowermost supported record from said supports to permit said record to move into playing position on said turntable.

30. 14. A record-changing apparatus comprising a rotatable turntable for receiving a record to be

played; two diametrically opposite supports with respect to said turntable for supporting a stack of records over said turntable by engaging portions of the peripheral edge of the lowermost supported record, one of said supports being adapted to be moved; a member extending upwardly from and being rotatable with said turntable in eccentric relation to the centering aperture of the lowermost supported record; and means operatively connected to said movable support for lowering the wall of the centering aperture of said lowermost supported record into the path of said member whereby the rotation of said member oscillates said lowermost supported record free of said supports to permit said record to move into playing position on said turntable.

15. A record-changing apparatus comprising a rotatable turntable, a pair of spaced supports adapted to support a stack of records above said turntable by engaging peripheral edge portions of the lowermost supported record, one of said supports being movable, a member extending upwardly from and being rotatable with said turntable in eccentric relation to the centering aperture of the lowermost supported record, a pickup arm for cooperating with a record on said turntable, a tripping mechanism actuated by said pickup arm when said pickup arm reaches the tripping groove of a record on said turntable, and means operatively associated with said movable support and said tripping mechanism for being actuated when said pickup arm reaches the tripping groove of a record on said turntable for moving the wall of the centering aperture of the lowermost supported record into the path of said member whereby the rotation of said member disengages the lowermost supported record from said supports to permit said record to move into playing position upon said turntable.

16. A record changing apparatus comprising a 40
rotatable turntable for receiving a record to be

played; two diametrically opposite supports with respect to said turntable for supporting a stack of records over said turntable by engaging portions of the peripheral edge of the lowermost supported record, a record receiving and centering spindle extending upwardly from and rotatable with said turntable, said spindle having an angularly extending camming portion formed thereon, and means operatively associated with

5 10 one of said supports for dropping the wall of the centering aperture of said lowermost supported record into engagement with the camming portion of said spindle for causing said record to be shifted thereby laterally to disengage its supported peripheral edge from the other of said supports to permit said record to move into playing position on said turntable about said spindle.

17. A record-changing apparatus comprising a rotatable turntable for receiving a record to be 20 played; two diametrically opposite supports with respect to said turntable for supporting a stack of records over said turntable by engaging portions of the peripheral edge of the lowermost supported record, a record centering spindle extending upwardly from and rotatable with said turntable, said spindle having an angularly extending camming portion formed thereon terminating in a portion the path of rotation of which lies below and traverses the centering aperture of the lowermost record of the stack, and means 25 operatively associated with one of said movable supports for dropping one side of said lowermost supported record to cause engagement by the wall of its centering aperture with the camming portion of said spindle whereby said record will be shifted laterally thereby to disengage its supported edge from the other of said supports and permit said record to move into playing position on said turntable about said spindle.
